UNITED STATES PATENT OFFICE

EDWIN P. S. NEWMAN, OF WASHINGTON, DISTRICT OF COLUMBIA

ICE GRID

Application filed February 4, 1929. Serial No. 337,424.

The present invention is an improved grid for the drawers or trays of ice making machines in which trays ice cubes for domestic use are formed. These grids divide the 5 trays into a plurality of compartments or spaces in which water is placed so that after the refrigerating operation a plurality of ice cubes are provided.

The grids generally in use are removable 10 from the drawer or tray and consist of a plurality of angularly disposed vertical partitions secured into a unitary structure or frame. After the refrigerating operation the ice tray is removed and held under running 15 water in an inverted position so as to cause the ice cubes impinging against the walls of the tray to be released. The result of this being that often many or all of the cubes of ice drop from the tray becoming dirty 20 or unusable and the hands become chilled or wet during the operation.

The object of the present invention is to provide an improved grid for cube making trays overcoming the drawbacks reenumerated 25 above, and wherein it is not necessary to invert the tray to secure removal of the ice cubes; where the grid may be removed from the tray without the hands touching the ice cubes or the grid per se; where the grid containing the cubes may be removed from the 30 tray and the cubes individually removed therefrom as desired.

The invention further has for its object the provision of a grid of the above stated character which is economical to manufacture, 35 durable and efficient and capable of performing the functions above reenumerated.

With these and other objects in view the invention further resides in sundry details 40 of construction, combination and arrangement of parts hereinafter more fully described and pointed out in the appended claims.

In the accompanying drawings, which illustrate several examples of an ice tray grid embodying the principles of the invention, 45 as at present devised:

Figure 1 is a perspective view of an ice cube tray or drawer with the improved grid 50 of the present invention having been raised

therefrom, and further illustrating the manner in which the ice cubes may be individually removed therefrom;

Figure 2 is a fragmentary sectional view of the grid taken substantially on line 2-2 55 of Figure 1;

Figure 3 is a perspective view of a grid of modified design and constructed in accordance with the present invention;

Figure 4 is a fragmentary sectional view of another modified construction embodying 60 the invention;

Figure 5 is a plan view of Figure 4;

Figure 6 is a fragmentary sectional view taken substantially on line 6-6 of Figure 65 4; and

Figure 7 is a plan view of a modified grid.

To accomplish the objects above enumerated, the removable grid for ice trays of refrigerating apparatus is provided with a plurality of vertical partitions 10, of suitable material, connected together in any suitable manner or design forming a unitary frame removable from the ice tray 11. The grid thus forms, when in the tray, a multiplicity of compartments 12 each producing an ice cube in a manner well understood in the art during the refrigerating operation, the grid per se being opened on its top and bottom sides.

These compartments 12 are such as are capable of preventing the ice cubes from falling or dropping therefrom, when the grid has been removed from the tray as shown in Figure 1, yet being opened at their bottom to permit the insertion of the grid in a tray of water in the usual manner previous to refrigeration and, further, for permitting a finger or other implement to be

inserted in the bottom of the compartment to assist in removing the individual ice cube from each compartment. The grid of course is preferably provided with a suitable handle 13 by which the grid containing all of the ice cubes can be removed from the tray after the ice therein has sufficiently thawed to release itself from the walls of the tray. Several examples are shown in the drawings for constructing the compartments to accomplish this purpose, although appli- 100

cant does not wish to be limited to any particular means.

In Figure 1 of the drawings the lower edges of the grid forming partitions are provided with laterally extending flanges 14 extending for a distance into each compartment of the grid to prevent the ice cubes from dropping from the grid even after they have melted to a considerable extent, or more than is necessary to release them from adherence to the surfaces of the partitions. These flanges are shown as continuous, but may only be smaller projections 14^a in contra-distinction to continuous, and moreover may not be provided on all walls of a compartment but only on one or possibly two of the walls as is necessary to accomplish the desired purpose. (See Figure 7.)

In order to prevent accidental lateral movement of the cubes from the outer compartments of the grid, which are only provided with three side walls, the outer ends of each partition or wall is provided with a like flange or projection 15 at its lower corner, which flange or projection 15 extends substantially upwardly for a distance with the outer edge of the partition, as shown in Figures 1 and 2. As shown in the drawings these projections or flanges 15 may be formed by a continuation of the flange 14.

The handle 13 may be of any suitable design or construction, but is here shown as of a bail type having its free ends inturned and received in suitable openings 16 formed in the partitions of the grid. As shown in Figure 1, the handle 13 is positioned centrally of the grid so that the same will be self-balancing and is connected with the outermost partitions so as not to interfere with the removal of the ice from the adjacent compartments. The side legs of the bail are slightly bent in order that the handle portion 13^a thereof will lie downwardly against a side edge of the tray 11, when the handle 13 is in its lowered position, and thereby not interfere with the insertions of the tray or drawer into the drawer opening of the refrigerator.

In Figure 3 a modified form of grid is shown which consists of a central partition 17 having spaced and laterally extending vertical partitions 18 extended therefrom. This form of grid permits the formation of an elongated ice cube, and, further eliminates the provision of central compartments closed by four side walls from which the removal of the ice is not as convenient as when the cube compartments have only three walls removed, thus enabling the ice cubes to be removed by the thumb and forefinger as shown in Figure 1.

Figures 4, 5 and 6 show a further modified form of grid, where the ice is prevented from dropping from the compartments of the grid by the vertical partitions 10^a thereof having

upwardly tapering surfaces, the lower corners of the outer ends of the partitions being enlarged to provide vertical and horizontal abutments 19 and 20 which restrict and limit movement of the ice downwardly and laterally from the compartment.

From the above it will be manifested that a very sanitary, novel and useful ice tray grid has been provided for overcoming many of the objections and drawbacks attendant with the grids now commonly in use. The ice cubes formed in the present grid need not be touched by human hand in order to effect their removal, but may be passed around in the grid which acts as a supporting or serving tray. The present invention also eliminates the now very disagreeable and unpleasant experiences in removing ice cubes from the tray by inverting the tray and holding same under water resulting in the loss of many cubes falling into a sink or other receptacle during the melting operation necessary to remove the cubes from the tray as is now commonly in practice, but on the contrary permits only those cubes that are desired to be conveniently removed, after the grid has been raised from the tray.

What is claimed is:

1. A grid for ice trays comprising a plurality of partitions relatively arranged to provide open ended ice molding compartments, said grid being provided adjacent one of said open ends of each compartment with laterally extended ice block supporting means shaped to restrict the area of the adjacent open ends of said compartments, whereby the ice blocks are prevented from falling through said open ends.

2. A grid for ice trays of refrigerating machines comprising a plurality of spaced angularly disposed partitions connected together to form the grid having upper and lower open ended ice molding compartments, said grid being removably insertable into a tray, and means at one of said open ends of the compartments to restrict the opening at said ends thereof for preventing ice blocks from falling from the compartments, when the grid is removed from the tray.

3. A grid for ice trays of refrigerating machines comprising a plurality of spaced vertical partitions connected together to form the grid, having ice molding compartments opened at opposite ends, corresponding open ends of the compartments being of less area than the other open ends thereof and a bail handle movably mounted on the grid permitting the latter to be suspended from the handle with the larger opened ends of said compartments uppermost and permitting the bail handle to be moved to an unobstructing position so that the tray and grid may be inserted into the freezing compartment of the refrigerating machine.

4. A grid for ice trays of refrigerating ma-

- chines comprising a plurality of connected vertical partitions relatively arranged to provide the grid having a number of ice molding compartments with upper and lower open ends and removably insertable in a tray, a handle by which the grid may be inserted into and removed from a tray with the upper open ends of said compartments uppermost, the lower open ends of the compartments being of less area than the upper open ends thereof, whereby the ice blocks are prevented from falling through said lower open ends, when the grid is removed from said tray.
5. A grid for ice trays of refrigerating machines comprising a plurality of connected vertical partitions relatively arranged to provide the grid having a number of ice molding compartments with upper and lower open ends and removably insertable in a tray, a handle by which the grid may be inserted into and removed from a tray with the upper open ends of said compartments uppermost, and means on at least one of said partition walls of each compartment to prevent the ice block therein from falling through the lower open end of the compartments, when the grid is removed from said tray.
6. A grid for ice trays of refrigerating machines provided by a plurality of intersecting vertical partitions forming the grid having ice molding compartments open at opposite ends and at one of their outer sides, each compartment being provided with laterally inwardly extending surfaces adjacent their open side and one of their open ends to support the ice blocks therein for a time after the ice blocks have thawed from frozen contact with the partition walls, whereby the said blocks are prevented from dropping from one of said open ends and said open side of said compartments.
- 30 7. A grid for ice trays of refrigerating machines provided by a plurality of intersecting vertical partitions forming the grid having ice molding compartments open at opposite ends and at one of their outer sides, each compartment being provided with laterally inwardly extending surfaces adjacent their open side and one of their open ends to support the ice blocks therein for a time after the ice blocks have thawed from frozen contact with the partition walls, whereby the said blocks are prevented from dropping from one of said open ends and said open side of said compartments, and handle means on the grid positioned to permit manipulation of the grid with the other open ends of the compartment uppermost.
- 35 8. A grid for ice trays of refrigerating machines comprising a plurality of spaced vertical intersecting partitions connected together in a unitary frame, handle means on the upper side of said grid by which the same may be inserted into and removed from a tray, abutments on the partitions at the lower edges thereof extending inwardly for a distance into the compartments formed between said partitions.
- 40 9. A grid for ice trays of refrigerating machines comprising a plurality of spaced vertical intersecting partitions connected together in a unitary frame, handle means on the upper side of said grid by which the same may be inserted into and removed from a tray, abutments on the partitions at the lower edges thereof extending inwardly for a distance into the compartments formed between said partitions, and abutments on the end edges of said partitions extending laterally for a distance.
- 45 10. A grid for ice trays of refrigerating machines comprising a plurality of spaced partitions forming ice molding compartments therebetween opened at their upper and lower ends, the openings at the lower ends of said compartments being of greater restricted area than the openings at the upper ends thereof, and a pivoted handle mounted on the grid, whereby the grid may be suspended from the handle with the upper ends of said compartments uppermost.
- 50 11. In combination, a grid for ice cube trays having a plurality of ice forming compartments, and a pivoted handle adjacent the top of the grid for removing the grid from the tray.
- In testimony whereof I have hereunto set my hand.
